UNITED STATES PATENT OFFICE.

JACKSON F. FRAZEE, OF SAN FRANCISCO, CALIFORNIA.

SUPPORT FOR PUNCHING-BAGS.

No. 823 594.

Specification of Letters Patent.

Patented June 19, 1906.

Application filed January 27, 1905. Serial No. 242,866.

To all whom it may concern:

Be it known that I, JACKSON F. FRAZEE, a citizen of the United States, residing in the city and county of San Francisco, State of California, have invented certain new and useful Improvements in Supports for Punching-Bags; and I do hereby declare the following to be a full, clear, and exact description of the same.

- 10 The invention is designed for the suspending of an ordinary punching-bag from the ceiling, rafters, or other overhead support, the object of the invention being to eliminate or reduce to a minimum the friction caused between the movable parts from which the bag is suspended, while at the same time overcoming the binding of the parts during the swinging movement of the bag and providing for the free movement of the suspension
- 15 cord or rope when the punching-bag is swung upward its full distance, which rope, with the supports generally employed, has a tendency to bite into the lower edge of the support as the punching-bag is swung upward, and thus prevents the full upward movement and uniform swing of the said punching-bag.

To comprehend the invention, reference should be had to the accompanying sheet of drawings, wherein—

- 20 Figure 1 is a view of the support secured to an overhead beam or ceiling, disclosing the suspension-cord attached at one end to the support and a section of a punching-bag connected to the lower end of the said cord. Fig.
- 25 2 is a detail vertical sectional view of the support, a section of the suspension-rope being illustrated secured within the rope-holding block of the support; and Fig. 3 is a plan view of the base-plate of the support.
- 30 The numeral 1 indicates a circular base-plate, which plate is designed to be secured to the ceiling or overhead support by any suitable means—as, for instance, by screws 3. This base-plate is formed with a depending
- 35 extension 4, within which is rotatably held the stem 5, said stem passing through a central opening in the depending extension 4 of the base-plate, being held in position by means of a nut 7, which nut holds onto the
- 40 stem 5 a cone 8. This cone 8 bears onto a series of balls 9, arranged within a circular seat 10, formed within the socket or bore 11 of the extension 4, which extension and the base-plate 1 may be formed integral.
- 45 The outer end portion 12 of the stem 5 is slightly enlarged and formed with a cone-

shaped shoulder 13, which shoulder when the stem is properly positioned, Fig. 2 of the drawings, bears onto a lower series of balls 14, arranged within a peripheral seat 15 in the outer edge or lower end of the extension 4. By this means there is provided a double ball-bearing surface for the rotatable stem 5, which reduces friction between the rotatable stem 5 and the extension 4 to a minimum, the stem being thus free to rotate with the least retardation of movement.

Onto the outer enlarged screw-threaded end 12 of the stem 5 is screwed the shell or thimble 16, which is formed with the depending claws 16', said claws holding the sphere or ball 17, which sphere or ball is free to turn or move within the cup-shaped seat 18, formed by the outer end of the enlarged portion 12 of the stem 5 and the securing-claws 16'.

The length of the claws 16', of which, preferably, three are used, is such as to embrace the sphere 17 for the greater portion of its circumference, thereby preventing the sphere falling from its position, although the same is free to rotate or turn freely in all directions within its seat 18. A universal joint is thus formed between the sphere 17 and the holder or thimble 16, which holder or thimble by reason of its engaging portion shall herein-after be referred to as a "sphere-holder."

The sphere or ball 17 has depending therefrom a short extension 19, to which is attached the rope-holder 19'. This holder is formed with a socket 20, which is intercepted by a side opening 20'. Through this side opening is inserted the upper end of the suspension-rope 21, which rope is secured therein by means of the small ball 22. This ball is inserted within the socket 20 prior to passing the suspension-rope through the opening 20', so that when the holder 19' is turned into a downward position, Fig. 2 of the drawings, and a slight pull exerted on the suspension-rope the ball 22 will move downward and bite into the rope, thereby "jamming," so to speak, and binding the said rope into the holder 19'. To the lower end of the suspension-rope is secured the punching-bag 23.

By means of the described support free movement is obtained in all directions, inasmuch as the stem rotates with little or no friction within the depending extension of the base-plate, and the sphere or ball, to which the suspension-cord holder is secured, being held to its holder by a universal-joint connection the same is permitted universal move-

ment to conform to the swinging movement of the punching-bag.

Having thus described the invention, what is claimed as new, and desired to be protected by Letters Patent, is—

1. A support for punching-bags consisting of a suitable base-plate having a depending extension, a stem rotatably secured within the extension of the base-plate and projecting therefrom, of bearing-balls within the said extension against which the rotatable stem works, a holder secured to the projecting end of the rotatable stem, a spherical member held within said holder so as to have universal movement therein, and a securing member for the suspension-rope carried by the spherical member.

2. A support for punching-bags comprising a suitable base-plate, a stem rotatably connected thereto, a holding-shell secured to the lower end of said stem, a spherical member loosely held within the shell of the said stem so as to have universal movement therein, and a suspension-rope holder secured to and depending from the spherical member, and ball-bearings interposed between the stem and the base-plate.

3. A support for punching-bags comprising a suitable base-plate, a stem rotatably connected thereto, a spherical member united to the said stem by a universal-joint connection, a suspension-rope holder secured to the spherical member, a socket in said holder for the insertion of one end of the suspension-rope, said socket being intercepted by a side opening in the holder and through which the end of the suspension-cord extends, and a

movable ball or lock device fitted within the socket of the rope-holder.

4. A support for punching-bags comprising a suitable base-plate, of a stem rotatably connected thereto, a spherical member held thereto by a shell depending from the rotatable stem, and a rope-holder secured to and depending from the spherical member.

5. A support for punching-bags comprising a suitable base-plate, of a stem rotatably held therein, ball-bearing between the stem and an extension of the base-plate, a spherical member connected to the stem by means of a shell carried by the stem, and means carried by the spherical member for uniting thereto one end of a suspension-rope.

6. A support for punching-bags comprising a suitable base-plate, an extension depending therefrom, circular seats formed therein, a series of balls arranged in each seat, a stem rotatably held within the said depending extension, cone-surfaces on the rotatable stem which bear onto the series of balls, a holder for a spherical member secured on the lower end of the rotatable stem, a spherical member held within said holder so as to have universal movement, and means carried by said member for the attachment of a suspension-rope thereto.

In testimony whereof I have hereunto affixed my signature in the presence of witnesses.

JACKSON F. FRAZEE.
